UNITED STATES PATENT OFFICE

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY

STROKE ADJUSTER FOR IDLE SHAPERS

Application filed September 16, 1927. Serial No. 219,925.

Certain types of machine tools have long been built to meet definite requirements in the art of metal working wherein a single cutting tool operates upon the work in a straight line motion. Such an operation is exemplified in the machine tool known as a shaper wherein the work is held on a supporting table and a cutting tool fixed against movement on a constantly reciprocating ram 5 engages the work and moves in a straight line relative thereto. The work table receives an intermittent motion between strokes of the ram at right angles to the line of motion of the ram and cutting tool where- 10 by a new portion of the work is presented to the cutting tool upon each forward cutting stroke thereof.

It was early found advantageous to provide the operating mechanism with adjustable means whereby the length of stroke could be varied in order, e. g., that the tool would not unnecessarily overrun the work or that the tool cut could be held to definite dimensions.

It was also conceived that indicator means in combination with the stroke adjusting means would be highly beneficial whereby the stroke could be set for predetermined amounts and accordingly various and ingenious devices were designed in combination with particular types of ram actuating and stroke adjusting means.

This invention has for its objects the provision of improved and simplified indicator means, and one which is especially advantageous in connection with the type of adjusting means including an adjusting shaft centrally mounted in the supporting hub of the driving gear unit. An indicator carrier is mounted on the end of the shaft but fixed to the driving member whereby the rotation of the adjusting shaft relative thereto is utilized to operate worm gearing and a dial mounted on the carrier. The dial is so mounted on the carrier that it occupies a horizontal position where it can be easily read when the ram driving mechanism is idle and in its most favorable position for adjustment. Also it necessarily follows therefore that the operator can easily tell

from the position of dial when the driving mechanism is advantageously positioned for adjustment.

The objects further include the provision of worm or screw threads at the outer end 55 of the adjusting shaft adapted to actuate the dial and which threads are also adapted to accommodate a nut which, through the intermediary of friction washers and the dial carrier, serves to lock the shaft to the driving member in its adjusted positions. 60

Two exemplifications of the invention are herein disclosed each having the major features outlined above embodied in a practical application thereof with certain accompanying 65 advantages which will be more evident from the detail description.

Other objects and advantages will be in part indicated in the following description and in part rendered apparent therefrom in 70 connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of 75 80 which:

Figure 1 is a side elevation of a shaper machine tool. Fig. 2 is a fragmentary detail view of the large driving gear mounted within the casing and showing parts of the stroke adjusting means. Fig. 3 is a vertical cross sectional view of the driving gear and its co-acting mechanism. Fig. 4 is an enlarged view of the outer end of the adjusting shaft and showing one form of the stroke indicator means mounted thereon. Fig. 5 is a vertical end view of the mechanism shown in Fig. 4 but with portions of the indicator carrier broken away to better 85 90 show the dial and its operating mechanism. Fig. 6 is an enlarged elevational view of a second form or modification of the indicator means. Fig. 7 is a vertical cross sectional view taken on the line 7-7 of Fig. 6; and 95 100

Fig. 8 is a sectional plan view taken on the line 8—8 of Fig. 7.

The invention is shown incorporated in a shaper, which is, as shown, more or less in general of a conventional type and comprises a main supporting frame and housing 10 and its base 11, having mounted in ways at the upper end thereof the ram 12 which carries the tool-head 13 at the outer end thereof and which tool-head has the cutting-tool 14 mounted in a suitable tool-holder 15, such tool 14 being adapted to receive a straight line motion from the reciprocations of the head in the usual manner in machines of this type.

The general construction includes a work-table 16 adjustably mounted on the cross-rail 17 adapted to be adjusted vertically along ways on the main housing 10.

The driving mechanism is conventionally shown as a train of gearing comprising gears 18, 19, 20, 21, 22 and the large bull-gear 23. The large driving gear 23 has integral therewith an outwardly extending drum-like hub 24 adapted to rotate in the bearing 25 of the main housing. Secured to the outer end of the hub 24 is a plate 25^a held in position on the hub by suitable set screws 26, such plate having an overhanging portion 27 adapted to engage the outer end surfaces of the bearing 25 to prevent inward axial movement of the driving gear-unit.

A cover-plate 29 is provided adapted to fit over the outer end of the driving gear-unit and to provide a housing for certain operating mechanism to be hereinafter described. The end-plate 25^a has an outwardly projecting central portion 30 upon which is mounted a hand wheel 31, which hand wheel has a bearing hub portion 32 inserted between the hub 30 and the bearing 29^a of the housing 29 and is rotatable relative to each.

Mounted on the hub 30 of the end-plate 45 is a cam 34 being rigidly fastened to the end-plate by set screws 35 to rotate therewith. A second cam 34^a is keyed to the hub 32 of the hand wheel 31 for adjustment relative to the cam 34, detent means 36 being provided to releasably hold the wheel 31 in its adjusted positions. A plunger 37 adapted to reciprocate in the bearing 38 co-acts with the cams. This plunger together with associated gearing at the lower end thereof 55 constitutes a means for rotating the shaft 39 which leads to the operating mechanism located in the cross-rail 17 for imparting an intermittent cross movement to the work table 16 between the strokes of the ram and 60 in proper timed relation thereto.

The above described mechanism for imparting movement to the work table forms the subject matter of a separate application Serial No. 197,797 filed June 10, 1927 and is, 65 therefore, only shown herein to an extent

sufficient to disclose the general organization, it being obvious that other table operating means may be resorted to in combination with the novel indicator means disclosed herein without materially altering the structure embodying the invention claimed in this application.

Returning to the more general features of the driving mechanism for the ram, such mechanism includes a lever or rocker arm 40 pivoted at its upper end to the ram 12 and being adjustable relative thereto and clamped in its adjusted position by means of the hand lever 41 in well known manner. The lower end of the rocker arm 40 is pivoted at 42 through the link 43 which, in turn, is carried by the fixed pivot 44. The bull-gear 23 carries thereon a crank pin 45 provided with a bushing 46, which serves as a bearing for the sliding block 47 held thereon by plate 47^a the block 47 being adapted to reciprocate along the slot 48 of the rocker arm 40 whereby the rotary movement of the bull-gear imparts an oscillatory movement to the rocker arm 40 and in turn a reciprocatory movement to the ram 12.

Means are provided for adjusting the crank pin 45 radially of the bull-gear 23 whereby the length of stroke of the ram may be varied, which consists of guide ways 49 formed on the driving gear having mounted therein the cross head 50 slidably secured therein by the plates 51 and which cross head carries the crank pin 45.

The means for adjusting the cross head along these ways consist of the adjusting shaft 52 extending in the direction of the axis of the driving unit and having a bearing in the hub portion 30 of the end-plate. The inner end of the shaft carries a bevel gear 53, which gear has a hub portion supported in the bearing 54 which also serves as a thrust bearing for the bevel gear.

Mounted on the driving gear 23 adjacent the inner end of the adjusting shaft 52 is a rotatable shaft 55 supported at one end in the bearing 56 formed on the gear-wheel and said shaft having at its opposite end a worm 57 adapted to engage with co-acting threads in the cross-head 50. The shaft has keyed thereon a bevel pinion 58 meshing with the bevel gear 53 on the adjusting shaft; the bearing end of the shaft 55 has thereon adjustable locking nuts 59 and washers 60 which co-act with the bevel pinion and the flanged portion 61 to hold the shaft against axial movement in its bearing 56. As may be seen rotation of the adjusting shaft 52 rotates the cross shaft 55 to adjust the crank pin 46 radially of the driving gear.

Stroke indicator means are mounted on the outer end of the shaft one form of which is fully illustrated in Figs. 3, 4 and 5. The means include a cylindrical carrier 63 which has an opening 64 adapted to receive the

extended hub portion 30 of the plate 24^a and is rigidly secured thereto by means of the set screws 65 whereby the indicator carrier revolves with the driving gear unit. 5 The outer end of the adjusting shaft 52 is provided with a squared end 66 which permits the application thereto of a suitable wrench for rotating the adjusting shaft relative to the driving unit. The adjusting 10 shaft is normally secured to the driving unit to rotate therewith by means of the nut 67, which, as shown, is a knurled nut adapted to be grasped by the operator but if desired may be of any other type of nut as, for 15 example, a wrench operated nut. The outer end of the adjusting shaft 52 is screw threaded as shown at 68, which screw threads receive the locking nut 67 and also are adapted to operate the dial indicator 20 means as will be later described.

The construction preferably includes a washer 69 rotatable with the adjusting shaft through a connection consisting of the pin 70 and key way 71. A friction washer 72 25 is interposed between the washer 69 and the indicator carrier 63. The periphery of the indicator carrier has a cut-away portion 73 in which the dial 74 is arranged. Rotatably mounted within the indicator carrier is a 30 stud 75, the stud being provided with an annular groove 76 coaxing with a set screw 77 which normally prevents the outward axial movement of the stud 75. The central portion of the stud 75 is machined to form 35 a worm wheel adapted to engage with the worm threads on the adjusting shaft 52. As shown the worm wheel 78 is integral with and forms part of the shaft but, as is obvious, may be separately formed and 40 assembled thereon if desired. The dial 74 in the above described embodiment of the invention is held directly on the outer end of the stud by means of the machine screw 79. The dial is graduated in a 45 desired manner to indicate the stroke of the ram, the ratio of the driving gears being such that the dial receives one complete rotation or slightly less for the entire range of stroke adjustment. The reading may be 50 determined by the index mark 80 on the indicator carrier.

Another form of the indicator carrier and dial means is shown in detail in Figs. 6, 7 and 8. In this embodiment the carrier 81 has a flattened external face upon which the dial rests being symmetrically arranged with respect to the carrier and in such a manner that its axis is substantially perpendicular to and intersects the axis of the adjusting shaft 52. A projecting hub 83 has fixed thereon the gear 84 adapted to mesh with the gear 85 cut integral with the stud 86 or secured thereon.

Both types of construction shown have 65 very decided advantages with respect to con-

venience in addition to the compact and simplified arrangement. The dial is arranged to have a definite position with respect to the position of the rocker arm 40. It is clear that the most favorable position for adjusting the crank pin 45 is that in which the rocker arm occupies a vertical position since in this position the crank pin may be moved without moving the rocker arm, assuming that the machine is not in 70 operation. Mechanism of this type is sometimes adjusted while the machine is in operation but in view of the fact that the shaft 52 rotates continuously with the driving unit such adjusting operation is extremely dangerous and cannot be accomplished with any very great degree of accuracy. This machine is designed primarily to be adjusted when the machine is idle and this condition enables an arrangement to be resorted to whereby the dial also serves to inform the operator when the driving unit is in a favorable position for easy adjustment. This arrangement consists in having the dial carrier and dial thereon so positioned that 75 when the dial is uppermost, as shown for example in Figs. 5 and 6 the rocker arm occupies a vertical position and the dial is presented horizontally in full view of the operator.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefor, such adaptations should be, and are intended to be, comprehended within the meaning and range of equivalency of the following claims:—

Having thus revealed this invention, I claim as new and desire to secure the following combinations and elements, or equivalents thereof, by Letters Patent of United States:—

1. A shaper combining, ram reciprocating means; means for adjusting the stroke thereof; an actuating shaft for said stroke adjusting means; and means for indicating the length of stroke in the adjusted positions comprising, an indicator carrier mounted on said shaft and fixed on said reciprocating means whereby said shaft may be rotated relative thereto, a stud mounted in said carrier, gearing connecting said stud to said shaft, and dial means on said carrier operatively connected to said stud.

2. A shaper combining ram stroke adjusting means; a manually operable shaft connected to said adjusting means; an indicator carrier mounted on said shaft the shaft being rotatable relative thereto; screw threads

on said shaft; a worm wheel mounted in said carrier engaging said screw threads; stroke indicator means mounted on said carrier connected to said worm wheel to be operated by said relative rotation; and a lock nut operable on said threads to lock said shaft in adjusted position.

3. A shaper combining a ram; driving means for reciprocating said ram; means for adjusting said driving means to obtain ram strokes of predetermined length; an actuating shaft for said adjusting means; and means for indicating the length of stroke in the adjusted position comprising, an indicator carrier mounted adjacent said shaft and fixed to said driving means whereby said shaft may be rotated relative thereto, screw threads on said shaft, a worm wheel mounted in said carrier engaging said screw threads, and indicator means mounted on said carrier to rotate therewith operated from said worm wheel said indicator means being so arranged on said carrier as to be uppermost when said driving means is in a favorable position for easy adjustment.

25 4. A shaper combining a ram; a pivoted arm connected thereto; a rotary driving member; means connecting said driving member to said arm for imparting an oscillatory movement thereto; a shaft arranged in said driving member in the direction of its axis; mechanism operated by movement of said shaft relative to said driving member for adjusting said connecting means to thereby vary the amplitude of said oscillatory movement and the stroke of the ram; an indicator carrier fixedly mounted on said driving member; a rotary stud mounted therein; gearing connecting said stud to said shaft; and stroke indicator means mounted on said carrier and connected to said stud.

45 5. A shaper combining a ram; a rotary driving member; transmission means connecting said driving member to said ram for imparting an oscillatory movement thereto; a shaft axially arranged in said driving member; means connecting said shaft to said transmission means for varying the stroke of said ram by adjustment of said shaft relative to said driving member; an indicator carrier mounted on said driving member to rotate therewith; a stud mounted in said carrier at substantially right angles to said shaft; gearing connecting said stud to said shaft; a dial mounted on the periphery of said carrier and adapted to conform to the exterior thereof; means for rotating said dial from said stud, the arrangement being such that when the dial is uppermost and substantially horizontal the transmission means is in its most favorable position for adjustment.

60 6. A shaper combining a ram; a lever arm connected thereto; a crank gear; a connection therefrom to said lever to oscillate the

latter; a shaft mounted in said crank gear, extending in the direction of its axis; means actuated by rotation of said shaft relative to the gear to adjust said connection and thereby vary the stroke of the ram; and means 70 to indicate the amount of adjustment and thereby the stroke comprising an indicator carrier fixed to said crank gear adjacent said shaft, a rotary stud mounted therein, worm gearing connecting said stud to said shaft, 75 and dial means mounted on said carrier operatively connected to said stud for indicating the stroke.

7. In a shaper, a ram; a pivoted rocker arm connected thereto; a rotary driving 80 member; a radially adjustable crank pin thereon adapted to engage said arm to oscillate the latter; a shaft mounted in said driving member adapted to be rotated relative thereto and connected to said crank pin for 85 adjustment thereof; and means to indicate the amount of adjustment of said crank pin and thereby the stroke of the ram comprising an indicator carrier mounted on said driving member to rotate therewith, screw 90 threads on said shaft, a worm wheel mounted in said carrier engaging said screw threads, and a dial on said carrier operatively connected to said worm wheel.

8. A shaper combining a ram; a pivoted 95 lever connected thereto; a rotary driving member for imparting an oscillatory movement to said lever; adjustable connections therebetween; a shaft mounted axially of said driving member and adapted to be rotated relative thereto; mechanism operative by said shaft to adjust said connections to vary the stroke of the ram; an indicator carrier positively fixed to said driving member to rotate therewith and having said shaft 100 extending therethrough; screw threads on the outer end of said shaft; a worm wheel mounted in said carrier engaging said screw threads; means operated by said wheel to indicate the length of stroke in adjusted 110 positions of said shaft; and a nut on said shaft end co-operative with said carrier to lock the shaft in adjusted positions.

9. A machine tool combining, a reciprocating member; a rocker arm connected 115 thereto; a rotary driving member; an adjustable eccentric pin thereon engaging said rocker arm to impart an oscillatory movement thereto; a shaft mounted in said driving member; means for rotating said shaft 120 relative to said driving member; connections from said shaft to adjust said eccentric pin; an indicator carrier mounted on the outer end of said shaft and positively held on said driving member to rotate therewith; screw threads on said outer shaft end; a gear mounted in said carrier engaging said screw threads; indicator means on said carrier operated by said gear to indicate the 125 position of said eccentric and thereby the 130

stroke of said reciprocating member; and a nut engaging said screw threads and co-operative with said carrier to lock said shaft in its adjusted positions.

- 5 10. A shaper combining a ram; a lever connected thereto; a rotary driving member for imparting an oscillatory movement to said lever; an adjustable connection therebetween for varying the stroke of said ram; 70
10 a shaft mounted in said driving member; means for rotating said shaft relative to said driving member; means for adjusting said connection by said relative rotation of said shaft and to thereby vary the stroke of 75
15 said ram; an indicator carrier mounted on said shaft and fixed to said driving member to rotate therewith; a stud mounted in said carrier; gearing connecting said stud to said shaft operated by said relative rotations; 80
20 and dial means on said carrier operated by said stud to indicate the ram stroke, said dial being so arranged as to be uppermost when the ram operating mechanism is in a favorable position for easy adjustment. 85
25 11. A shaper combining, a ram; operating mechanism therefor comprising, a rocker arm pivoted thereto and a rotary driving member having an adjustable connection to said arm for oscillating the latter; an adjust shaft mounted in said driving member; means for rotating said shaft relative to 90
30 said member; mechanism operated by said relative rotation for adjusting said connection; an indicator carrier mounted on said shaft and fixed to said driving member to rotate therewith; a stud mounted in said carrier; gearing connecting said stud to said shaft; dial means for indicating the ram stroke mounted on said carrier and 95
35 operatively connected to said stud, the axis of said dial being substantially at right angles to said shaft and said dial being arranged to be uppermost when said operating mechanism is in a favorable position for adjustment. 100
40 12. A shaper combining ram reciprocating means including a rotary driving member therefor; means for varying the length of stroke of said ram; an operating shaft for said last named means mounted in said driving member and rotatable relative thereto; indicating means secured to said driving member and disposed to rotate about an axis transverse to the axis of driving member; and reduction gearing for connecting said 105
45 rotary indicating means to said shaft whereby a plurality of rotations of said shaft relative to said driving member results in less than one rotation of said indicating means on its own axis. 110
50 13. A shaper combining a ram; a pivoted lever connected thereto; a rotary driving member; a crank pin thereon operable in a slot in said lever for imparting an oscillatory movement to the latter; means for adjusting 115
55 said pin radially of said driving member. 120
60 14. A shaper combining ram reciprocating means; a rotary driving member therefor; adjustable connections between said driving member and reciprocating means for varying the stroke; a shaft for operating said adjustable connection extending thru said driving member; an indicator carrier mounted on said driving member with the outer end of said operating shaft extending therethru; a dial operating stem mounted in said carrier extending transversely to said shaft; gearing connecting said stem with said operating shaft; rotary indicating means located in the periphery of said carrier; and operating connections between said stem and indicating means, the arrangement being such that when the indicating means is uppermost the mechanism is in a favorable position for easy operation of said adjustable connection. 125
